UNITED STATES PATENT OFFICE.

THOMAS J. DOBBINS, OF BROOKLYN, NEW YORK, ASSIGNOR TO CHESEBROUGH MANUFACTURING COMPANY (CONSOLIDATED), OF NEW YORK, N. Y., A CORPORATION OF NEW YORK.

DESIGN FOR A TUBE CAP.

Application filed December 9, 1922. Serial No. 4,533. Term of patent 14 years.

To all whom it may concern:

Be it known that I, THOMAS J. DOBBINS, a citizen of the United States, residing in the borough of Brooklyn, county of Kings, city and State of New York, have invented a new, original, and ornamental Design for a Tube Cap, of which the following is a specification, reference being had to the accompanying drawing, forming part thereof.

Figure 1 is a plan view of a tube cap showing my new design, and

Figure 2 is a side elevation of the same.

I claim:

The ornamental design for a tube cap as shown.

THOMAS J. DOBBINS.
